UNITED STATES PATENT OFFICE.

JOHANN JAKOB DETTWYLER-BRÜDERLIN, OF SISSACH, SWITZERLAND.

LETTER-FILE.

No. 851,870.

Specification of Letters Patent.

Patented April 30, 1907.

Application filed July 24, 1905. Serial No. 271,076.

To all whom it may concern:

Be it known that I, JOHANN JAKOB DETTWYLER-BRÜDERLIN, a citizen of the Swiss Republic, residing at Sissach, Canton Basel-Land, Switzerland, have invented certain new and useful Improvements in Letter-Files, of which the following is a specification.

The present invention relates to a letter file wherein the documents are not perforated but are held in a sheet metal frame by means of a spring pressed bar, the latter being connected by the spring to a hinged wall of said frame.

15 The invention is shown in the annexed drawing in which

Figure 1 is a plan view of the letter file with the covers opened. Fig. 2 is a side elevation thereof with the frame partly broken away. Figs. 3 and 4 are a side elevation and plan respectively, of the hinged wall of the sheet metal frame before referred to.

On the back 1 of the letter file, which is provided with two covers 2 and 3, is fixed an open sheet metal frame consisting of three fixed members or walls 4, 5 and 6, and having a suitable height. The said frame is closed on its fourth side by a hinged wall or flap 7, which is suspended at one end in the wall 6 of the frame as at 11 and at the other end is adapted to be connected to the opposite wall 4 by means of a spring pressed bolt 8 engaging a slot 9 in said wall 4. The said hinged wall 7 is of U shaped cross-section except at its ends. The bolt 8 is held in the wall 7 by the sides of said wall which are bent over the bolt as at 8^a, Fig. 4, and one of said sides has a slot 18 through which passes a pin 10 screwed into the bolt, said pin and slot permitting the bolt to be withdrawn from the slot 9 in the wall 4 and therefore of rotating the wall or flap 7 around the pivotal point 11.

A guide pin 20 is fixed to the wall 7 and around said pin is located a coiled spring 13, adapted to normally press the bolt 5 in a forward direction into the slot 9 and keep said bolt in closed position. On said hinged wall 7 adjacent the point where said wall is suspended in the wall 6, is riveted a flat spring

12, the free end of which extends to about 50 the center of the frame and passes between the two side members of a bar 19 of U-shaped cross section. A pin 14, is passed over the spring 12 through both members of the bar for the purpose of removing or lifting said bar when the side wall 7 is swung open about the point 11. On the frame part 5 near the walls 4 and 6 are fixed pins 15 and 16, which act as guides for the bar 19.

The bar is pressed against the frame part 60 5 by the spring 12, when the letter file is empty but by displacing a bow or slide 17, placed over or around the hinged wall 7 and spring 12, the bar can be kept at the requisite distance from said frame part 5 to exert 65 the desired pressure on the documents placed in the file.

For inserting the documents in or removing them from the file, the connection between the two sides or walls 7 and 4 of the 70 frame is unfastened by withdrawing the bolt 8, whereupon the wall 7, to which the spring 12 and bar 19 are attached can be rotated round the pivotal point 11.

What I claim as my invention and desire 75 to secure by Letters Patent of the United States is:—

1. In a letter file the combination of a sheet metal frame inserted therein and having three fixed walls, a hinged wall suspended 80 in one of said fixed walls, a spring attached to said hinged wall, a bar acted upon by said spring, means for regulating the pressure of said spring on the bar, and means for detachably connecting said hinged wall to the 85 frame aforesaid substantially as described.

2. In a letter file the combination of a sheet metal frame inserted therein and having three fixed walls, a hinged wall suspended 90 in one of said fixed walls, a spring attached to said hinged wall, a bar acted upon by said spring, means for regulating the pressure of said spring on the bar, and a spring pressed bolt adapted to detachably connect said hinged wall to the frame aforesaid substantially as described.

3. In a letter file the combination of a sheet metal frame inserted therein and hav-

ing three fixed walls, a hinged wall suspended in one of said fixed walls, a spring attached to said hinged wall, a bar of U section acted upon by said spring, a slide on said 5 hinged wall adapted to regulate the pressure of the spring on the bar, guides for the latter and a spring pressed bolt slidably mounted in said hinged wall and adapted to detachably

connect the latter to the frame aforesaid substantially as described.

In witness whereof I have signed this specification in the presence of two witnesses.

JOHANN JAKOB DETTWYLER-BRÜDERLIN.
